STRAP FASTENING DEVICE

Michael J. McAneny, deceased, late of Hillsboro, N. Mex., by Ann L. McAneny, administratrix, New Buffalo, Mich., assignor to Lewis M. Schott, Plandome, N.Y.

Application March 19, 1958, Serial No. 722,486

3 Claims. (Cl. 140—93.4)

This invention relates to improvements in a strap fastening tool or device for banding or strapping bundles, packages and assemblies of diverse shapes with tensioned metal straps and cooperating fastenings. More particularly, it relates to improvements in strap tensioning and fastening tools of the type described and claimed in the copending application for Strap Fastening Device, Serial No. 690,598, filed October 14, 1957, now abandoned.

One of the objects of the invention is the provision of a tool or machine which, in a manual operation thereof, tensions or tightens the strap about the material or package to be bound, severs the strap to the required length, and forms and associates an untensioned end portion of the strap in a portion of a cooperating buckle.

A further object of the invention is the provision of a device so designed and constructed as to be more effectively employed in efficiently banding pipes, pipe connections and all types and shapes of assemblies, bundles, bales or packages having curved or straight surfaces.

Another object of the invention is the provision of a tool having an adjustable head constructed for cooperation with straps and buckles of different widths and thickness and provided with improved means for holding the strap tensioned adjacent a free end thereof so as to provide for forming and sealing an untensioned free end of the strap in anchoring engagement with a cooperating buckle.

Another object of the invention is the provision of a strap fastening device which can be quickly brought into and out of engagement with a buckle and strap to be fastened, for sequentially tensioning, cutting, forming and sealing the strap into end engagement with the buckle by unitary means controlled by a single operating lever.

Other objects and advantages of the invention will become apparent from the following specification and by reference to the accompanying drawings forming a part thereof and in which:

Fig. 1 is a side elevation of a tool constructed in accordance with the teachings of this invention;

Fig. 2 is a top plan view of the tool;

Fig. 3 is a fragmentary, longitudinal sectional view through the tool of Fig. 1 showing the tool in strap tensioning position;

Fig. 4 is a section similar to Fig. 3 with the tool approaching the strap cutting position;

Fig. 5 is a section similar to Fig. 3 with the tool in the strap forming position;

Fig. 6 is a section similar to Fig. 3 with the tool in the strap and buckle engaging position;

Fig. 7 is an enlarged fragmentary bottom plan view of the tool;

Fig. 8 is a fragmentary side view showing the head hinging means;

Fig. 9 is a perspective view of a buckle which may be employed with the tool of the invention;

Fig. 10 is an enlarged fragmentary sectional view of buckle and strap engaging mechanism;

2

Fig. 11 is a view similar to Fig. 10 showing the size adjusting means for the tool; and

Fig. 12 is a perspective view of one of the cam elements shown in Figs. 10 and 11.

5 Having reference to the drawing, wherein corresponding reference numerals represent corresponding parts throughout the several figures, the banding tool comprises a substantially rectangular frame composed of spaced parallel longitudinal side rail portions 10, 10', a rear transverse tie and base portion 12 disposed between the rail portions and fixed thereto as by bolts 14 and pins 16 at the rear end of the rails and provided with a rearwardly extending handle 18 for manipulating the tool. The lower end of the base portion 12 is suitably shaped to provide a rear foot support and a guide slot 20 opening laterally for receiving the strap.

The rail portions are each provided with flared front end extensions 22 and 22' at the forward end for mounting therebetween laterally adjustable buckle engaging means 24. Also attached to the flared extension is an adjustable head member 26, presently to be described, embodying manually operable laterally adjustable strap receiving and engaging means for straps of different widths, and means for holding a tensioned strap passing through the head and around an object to be banded.

25 Slidably disposed for longitudinal reciprocating movement on the side rail portions 10, 10', between the rear transverse member 12 and the buckle engaging means 24, is a strap receiving mechanism which serves to grip and pull or tighten a strap 28 passing through a buckle 30, Fig. 9, and the tool and about the body to be banded, to cut the strap adjacent and rearwardly of the buckle, to form or shape the resulting rearward extension of the strap beyond the buckle, to fold it over and into the buckle, and finally to iron or seal the strap end and the buckle into an effective and strong connection.

30 This mechanism includes a slide 32 grooved longitudinally on its opposite sides for guiding engagement with the side rails 10, 10' of the frame. The slide is preferably an integral casting constructed to provide a transverse rear wall portion 34 having spaced upwardly and rearwardly extending lugs 36, spaced forwardly extending parallel side wall portions 38, 38', and a horizontally disposed bottom or ledge portion 40 providing a strap rest, cutter block and anvil. Slide 32 also includes a laterally opening horizontal slot 42 in substantial alignment with slot 20, and above the ledge portion 40 for passage of the strap into and out of overlying engagement with the ledge cutter block and anvil. The slots 20 and 42 permit lateral engagement, and disengagement of the tool with the strap 28. At its front end the ledge has a relatively pointed nose 44 and immediately to the rear and on the top side thereof has a forwardly-sloping surface 46 terminating at its front end in a semicircular depression 48.

35 Directly to the rear of this sloping surface 46 there is provided a transverse recess 50 defining with the sloping surface a transverse cutting edge 52. All of these parts of the ledge portion function cooperatively during the forming and cutting operations on the strap in conjunction with a manipulatable combination tool hereinafter described.

40 Surmounting the transverse rear wall portion 34 of the slide and pivotally mounted on stud shaft 54 having its ends fastened in apertures in lugs 36, is a latch member 56.

45 The latch 56 consists of a single element with a bifurcated forwardly extending arm 58 defining a slot 60 for free movement therein of bar 62, between the upper and lower arms 64 and 66 respectively. Arm 64 is provided in its forward end with a recess 68 for receiving bar 62 in one position of the latch and a cam 70 on

its top side adapted to be engaged by projection 72 on lever 74 in certain movements of the lever.

The latch is provided with a downward extending arm 76 having its lower end provided with notches 78 and 80 for cooperative engagement with arm 82 of a leaf spring 84 disposed over the rear wall portion 34. The free arm of the spring is adapted to engage in one or the other of the notches in the controlled positioning of the latch during manipulation of the tool.

Disposed in the forward recess of slide 32, defined by the side walls and ledge portion thereof, and pivoted at its lower end by stud shaft 86, having ends thereof extending through side walls 33, 38', is a vertically swinging combination tool element or rock member 88 which cooperates with parts of the ledge portion in gripping, cutting, forming and sealing the strap to the buckle. At its lower rear end this rock member 88 is provided with a bore into which is mounted for limited pivotal movement a gripping pawl 90 having a flat foot portion 92. When member 88 is rocked counterclockwise pawl 90 serves as a gripping pawl by gripping the top side of the strap and clamping it firmly against the top of the ledge portion 40. Spaced forwardly of the pawl 90 and extending transversely of the lower side of the rock member is a cutting edge 94, and adjacent the cutting edge 94, forwardly thereof, there is a transverse groove or recess 96 for receiving the cut or sheared end of the strap in the manner shown in Fig. 3. The cutting edge 94 cooperates with cutting part 52 on the ledge portion to cut the strap 28 in a controlled clockwise rocking movement of the combination tool or rock member. Groove 96 together with a boss 98 transversely of the rock member which cooperates with the depression 44 in the slide block 32 define a U-shaped die, to form and upwardly bend the severed end portions of the strap in the manner shown in Fig. 5.

At its lower front or corner end the rock member 88 has a substantially U-shaped transverse die portion 100 which functions to press and seal the upwardly bent end of the strap downwardly in arched-like fashion against and into coupling engagement with the buckle, as seen in Fig. 6.

The upper part of this second die portion terminates in a forwardly facing projection 102 which, in a forward sliding movement of the slide, functions to contact the upwardly bent tip end of the strap and, in forward movement of the slide and rock member, impart a slight lift to the strap end in order to insure positive subsequent engagement of the die portion 100 with the strap and to force it over and into coupling engagement with the buckle.

The rock member is also provided with two spaced parallel upstanding lever arms 104 which serve also as lever mounting lugs. The transverse stop bar 62 is connected between arms 104 in position to cooperate with latch members 56 hereinbefore described.

The slide and rock member mechanism is arranged to perform the operation of tightening the strap about the body to be bound and through the buckle when moved in one direction, while the remaining operations are performed when the mechanism is moved in the opposite direction. The tightening, cutting, forming and sealing operations being cooperative steps in producing the new and improved strapping and sealing method. Slide 32 and associated rock member 88 are shifted or operated manually to their respective operating position by means of the vertically swinging handle or lever 74, pivoted at its front end at 106 between the pair of upstanding arms 104 rising from the rock member 88, and a pair of toggle links or levers 108 pivotally connected at their forward ends to an intermediate portion of lever 74 by pivot 110 and pivotally connected at their other ends to upstanding lug 112 on the tie member 12.

Between member 12 and slide 32 is a resilient stop for cushioning rearward movement of the slide, such stop preferably consisting of a plunger 114 backed by spring 116 in recess in member 12; the spring and plunger as-

sembly being retained in the recess by a screw threaded guide 118. As more clearly shown in Figs. 3 and 4 the extended end of plunger 114, on the rearward travel of the slide block 32, passes through a bore 120 in latch member 56 so that the head of the plunger strikes the back face of element 34 of slide block 32. This resilient stop also tends to urge the slide forwardly from a retracted position and thereby facilitate rapid operation of the tool.

The slide may if desired be held at predetermined points of its travel along side rails 10, 10' by spaced detents 122 provided in the opposite rails and cooperating spring pressed ball latches 124 in opposite sides of the slide, the balls engaging in the detents at the predetermined positions until released therefrom by movement of lever 74.

At their forward ends, rails 10, 10' are each provided with opposed inwardly directed flanges or shoulders 126 serving as stops limiting forward movement of slide 32 and as vertical rear backing supports for the pair of laterally adjustable counterpart buckle engaging members 24, as more clearly seen in Figs. 10 and 11. Members 24 are slidably mounted on rod 128 supported between the upper forward ends of rails 10 and 10'. The rear buckle supports 24 have slotted front faces into each of which one leg 130 of a pair of L-shaped sliders 132 is adapted to fit.

Sliders 132 are mounted for lateral movement on shaft 134 carried between plates 136 and 136' of head piece 26. The extended end portions of shaft 134 are threaded and each end receives a knurled nut 138, one face of which engages the outermost face of its cooperating slider 132.

The other faces of slides 132 engage one of a plurality of spacer keys 140.

The spacer keys 140 are pivotally mounted on the head piece 26 by stud shaft 142 carried by plates 136 and 136'. As shown in, for example, Figs. 2 and 11, three key members 140 are positioned between inner stop element 144 of shaft 134 and the inner faces of each slider 132, thus the rear buckle supports are in their most extended position to receive the largest buckle.

For effecting lateral adjustment of member 24 to accommodate buckles of different size, one or more of the keys 140 are pivoted upwardly about stud shaft 142 so that their other ends are out of engagement with shaft 134 whereby nuts 138 may be screwed toward one another. The inward movement of nuts 138 bring about corresponding inward movement of sliders 132 which, in turn, move rear buckle support elements 24 inwardly.

Members 24 have at their lower ends depending hook-like buckle rests 146 for detachable gripping engagement with the rear ends 148 of the side flanges of the buckle 30 as shown in Fig. 9.

Each slider 132 is provided with a downwardly extending pin 150 for cam track engagement, with a cooperating cam track 152 on cam element 154 to be more fully described hereinafter.

The lower extensions 156 of rails 10 and 10' are contoured on their upper surfaces at 158 to provide a curved seating surface, guide flange and support for swinging and pivotal movement of the adjustable strap engaging head 26. Each of the spaced parallel side members 136 and 136' is contoured at a lower rear edge portion 160 thereof to cooperate with the curved seating and guiding surfaces of the rail extensions 156. Paired links 162 and 164 are pivotally connected at 166 and 168 to a side member of the frame and provided with a trunnion 170 and 172 extending into an aperture provided in extensions 156, serving to provide vertical swinging movement of the head.

The pivotal connections 166 and 168 for links 162 and 164 are provided with lock nuts 174 so that the head may be in an intermediate position by tightening the nuts. The head 26 is conveniently held in a position for use of the tool on flat surfaces by latch 176 pivotally mounted on the extension 156 of rail 10'. Latch 176 includes an operating boss 178 and a keeper element 180' which

engages offset 182' on the upper surface of link 164 when the head is pivoted to bring about the mating of surfaces 158 and 160. From this position the head may be swung downwardly for strap binding and fastening operations in connection with work having curved or other irregular surfaces. The side members of the head frame constitute in reality movable rail extensions at the front of the tool.

Disposed in parallel relation to the rear buckle engaging members 126 and mounted for movement toward and away from each other on transverse guiding support 180, fixed at its ends in side frames 136 and 136', are strap engaging jaw members 182. These jaws, at the bottom thereof, have inwardly facing horizontal slots and opposed projections 184 for releasable supporting engagement beneath the marginal side edges of the strap, as illustrated in Figs. 3 through 6. Jaw members 182 are also provided with projections 185 positioned forwardly of strap supporting projections 184. Projections 185 engage a portion 149 of the front cover of the buckle 30 as shown in Figs. 3 through 6. Each jaw member is provided with a side flange 186 which rotatably engages cylindrical cam 154 and is held against axial displacement relative thereto by engagement of the flange 186 in a groove 188 between a facial portion of the cam and a spaced annular flange thereon. A splined axle 190 having its ends journaled in the side frames 136 and 136' serves jointly with the support 180 to guide the jaws 182 and cams 154 toward and away from each other. Spiral cam track 152 receives in a portion of its periphery one of the pins 150. A suitable knob or handle 192 is fixed to an end extension of axle 190 by which the axle may be turned to rotate cams 154 splined thereon. By this rotation of the axle 190, the cams 154 and the jaw members 182 are caused to slide toward and away from each other on their supports to grip and release the strap and buckle, the pins 150 effecting such movement by engagement in the cam tracks 152.

Each of the strap engaging jaws is provided with means for effectually clamping the strap 28 to the tool immediately forward of the buckle during the operation of tensioning the strap about a body and subsequently sealing it to the buckle. This clamping action takes place simultaneously with that of the movement of the cams 154 and the jaws 182 to the strap engaging position.

The clamping is accomplished by generally vertically sliding dogs 192. A dog 192 is mounted for sliding movement by flanges 194 and 196 which engage corresponding recesses in each jaw member 182 to receive it so that the dog is in the operating path of the associated cam and in a plane intersecting the companion supporting jaw extension 184, as shown in Figs. 3 and 10. The lower end of each dog 192 is provided with a pivot foot 200 having gripping teeth 202 for engagement with the strap overlying jaw lug 184.

The dogs 192 fit loosely in the slots in sliders 132 and a pair of springs 206 and 208 urge each dog upwardly and forwardly so that toothed foot 200 is normally in a strap engaging and holding position when the dogs are cammed downwardly as to be more fully described hereinafter.

Referring specifically to Fig. 3, the dogs 192 are shown in the strap holding position and as shown, strap 28 may be urged by action of slide block 32 toward the rear support 12. However, the strap is restrained from moving in the opposite direction.

Each cam 154 controls movement of its associated strap gripping jaw into and out of gripping position with the strap, and movement of its associated dog into and out of gripping position with the strap. The arrangement is such that when the splined axle 190 is rotated counterclockwise, the jaws are released from their gripping position, and when the axle is rotated clockwise the jaws are caused to engage the strap.

The cam tracks 210 are of such disposition and length as to provide lateral releasing movement and strap en-

gaging movement of the gripping jaws for all adjusted positions of the buckle engaging means. The respective cams 212 on each dog are contoured to be out of engagement with tracks 210 during the movement of the jaws into and out of strap clamping position, so that the dogs are maintained during such travel out of gripping contact with the strap. Further, the peripheral cam surface arrangements are such that the strap is gripped by the dogs simultaneously with the movement of the gripping jaws into strap engagement. Conversely, release of the dogs from their strap gripping engagement is accomplished simultaneously with the release of the gripping jaws from strap engagement.

The strap gripping jaws together with the dogs constitute a vise for gripping the strap and retaining the tool thereon during tensioning of the strap and subsequent operation to be performed thereon. It is to be noted that the overlying portion of the strap extending rearwardly through the buckle from the dog gripping point is untensioned when cut for folding over and fastening to the buckle. This obviates the necessity of bending the strap at a tensioned portion thereof.

The operation of the structure hereinbefore described may be briefly stated as follows: A metal strap or band 25 extending through the buckle with its end attached to the buckle as in Fig. 3 is placed around the objects to be bound with the opposite end of the strap extending through the buckle in a reverse direction. The tool, with the cam operating axle rotated in a counterclockwise manner in which the strap engaging jaws are open, is engaged laterally with the strap and forced forwardly until the buckle rests engage the side flange portions of the buckle. In this position, the cam operating axle is turned clockwise shifting the strap gripping jaws from their full open 30 position to a closed strap engaging position. Simultaneously with engagement of the strap by the jaws the pawls 200 are urged into engagement with the strap, the dog lever arms having contacted the high portion 210' of the cams. This causes the tool to be retained on the strap with the strap engaged between the gripping jaws against withdrawal from the buckle but permits a drawing movement of the strap through the buckle by the tool.

Following engagement of the tool with the strap and buckle, the handle 74 is swung to cause pawl 90 of rocker 45 88 to be elevated above the strap and the slide to slide forwardly a distance determined by the movement of the handle as shown in Fig. 4. Swinging of the handle in a reverse direction causes pawl 90 to grip the strap against the slide which is forced rearwardly to tension the strap 50 through the buckle, the tension thereof being held beyond the buckle by engagement of the dogs 192 with the strap. This operation may be repeated as desired to effect complete tightening of the strap through the buckle and around the object.

55 In the strap tensioning movement of the slide 32 the arm 76 of latch member 56 is in the forward cooperating engagement with arm 82 of the leaf spring 84 so that the pin 62 limits forward rocking movement of the rocker 88. Figs. 3 and 4 show the latch member 56 in the forward index position. The other position of latch member 56 is ill-

60 lustrated in Figs. 5 and 6. The latch member 56 is moved from the rearward position (Figs. 5 and 6) to the forward position (Figs. 3 and 4) by moving the handle 74 all of the way forward which causes slider 32 to move to its most rearward position. The rearward movement is cushioned by spring urged pin 114 engaging member 34 of the slider 32. As the pin 114 is urged inwardly by the rearward movement of slider 32 the forward or head end of guide 118 strikes leg 76 of latch member 56 and indexes it to its forward position on spring 82.

65 When the strap is sufficiently tensioned, and severing and fastening of the untensioned cut end to the buckle is desired, the slide is caused to be moved to a forward position wherein the latch 56 is tripped by the camming action between projection 72 on lever 74, and the cam 70

of latch 56, indexing leg 76 to its rearward position on spring 82. This allows further clockwise rocking of member 88 as pin 62, carried between arms 104 of the rock member 88 moves from between the slot in latch member 56.

The clockwise movement of the member 88 cuts the strap and bends its end upwardly by the cooperating cutting and bending die portions thereof and the anvil on the slide as shown in Fig. 5. After cutting and forming the strap, slide 32 together with its rocker member 88, is moved by the handle rearwardly until the forward end of the rocker is disposed rearwardly of the bend end of the strap, after which the slide is again advanced to cause the die member of the front end of the rocker to initiate an upward folding movement of the strap end portion to fold the strap end over the upper side of the buckle and force the end thereof under the arch of the buckle as shown in Fig. 6. In this movement the untensioned severed end of the strap is in effect bent around the buckle and ironed into substantially flat engagement with the top of the buckle and with the end of the strap confined by the buckle arch. The strap having been tensioned, cut, formed and folded over into the buckle, cam operating axle 190 is turned counterclockwise and the machine is released from strap and buckle engagement.

In a normal strapping operation on a substantially flat surface, the forward rail extensions or head occupies a substantially horizontal position as shown in Figs. 3-6. In a hose clamping operation or in strapping a cylindrical or other object of irregular contour, the head is swung downwardly as desired to enable the tool to substantially conform to the object at the point of fixing the strap as shown in Fig. 8. Referring particularly to Fig. 8, the employment of the double pivot points 170 and 172 for the head 26 is effective to project the pivotal axis of the head relative to the body of the tool to point A substantially at the forward tip of the front buckle holding means of sliders 182. By selecting point A as the pivot point the relative spacing between the front and rear buckle holding means is maintained the same regardless of the position of the head relative to the body of the tool. The arrangement is such that strapping is made possible for much smaller cylindrical and other shaped objects than could heretofore be strapped. The pivoted head arrangement results in a universal tool with a much larger strapping range, and the entire strapping operation of tensioning, cutting, forming and sealing is made possible in a single tool.

The invention has been described in connection with a preferred embodiment thereof but the words used are those of description and not of limitation, and modifications and changes within the purview of the appended claims are contemplated without departing from the true scope and spirit of the invention.

This application is a continuation-in-part of application Serial No. 690,598, filed October 14, 1957.

What is claimed is:

1. A strap fastening tool comprising a frame having means thereon to detachably receive a buckle to which one end of a banded strap is connected, said buckle-receiving means including laterally adjustable members having rests thereon for supporting the marginal side edges of the buckle, a frame extension forwardly of said buckle-receiving means, laterally displaceable means mounted on said frame extension adjacent, said buckle-receiving means adapted to receive and clamp thereto the other end of the strap to be fastened to the buckle, and means mounted on said frame and operatively connected to said strap-receiving means for actuating the same toward and from each other into and out of engagement with the marginal side edges of the strap, means

pivoting the frame extension to said frame, said pivoting the frame extension to said frame, said pivoting means comprising a pair of spaced swingable link connections between the main frame and the frame extension on each side of the tool with the spaced links of each pair having spaced pivotal connections at one end with the tool frame and at the other end with the frame extension to provide swinging movement of the frame extension with respect to the tool frame in angular adjustment of the frame extension with respect to the tool frame.

2. A strap fastening tool comprising a frame, buckle-receiving members mounted on said frame for lateral adjustment toward and from each other and having rests at their lower ends for supporting the marginal side edges of a buckle, an adjustable frame extension, strap-engaging members mounted on said frame extension forwardly of said buckle-receiving members for lateral displacement toward and from each other into and out of receiving engagement with the strap, spring pressed gripping elements pivoted on said companion strap-engaging members for releasably-clamping the strap thereto, and means for actuating said strap-engaging members into and out of their strap-engaging positions and for controlling the displacement of their gripping elements, into and out of their clamping positions, said means including spirally-grooved cams operatively connected to said members to travel laterally therewith and free to turn relatively thereto, coupling pins engaging the grooves of the companion cams, an operating handle jointly connected to said cams for turning them in one direction or the other to correspondingly displace the strap-engaging members into and out of their operative position, said cams having portions thereon in governing relation with said gripping elements for causing their simultaneous displacement into and out of clamping engagement with the strap, means pivoting the frame extension to said frame, said pivoting means comprising a pair of spaced swingable link connections between the said frame and the frame extension on each side of the tool with the spaced links of each pair having spaced pivotal connections at one end with the said frame and at the other end with the frame extension to provide swinging movement of the frame extension with respect to the frame in angular adjustment of the frame extension with respect to the frame.

3. In combination, a strap fastening tool having a main frame with means thereon transversely adjustable with respect to the frame for detachably engaging and holding a buckle and a manually operable strap gripping, tensioning, cutting, forming and sealing means supported for sliding movement on the main frame rearwardly of the buckle engaging means to draw a strap through the buckle, cut and form its end and seal it into the buckle, a frame extension, means on the frame extension transversely adjustable with respect thereto for detachably engaging and holding adjacent said buckle engaging means a strap passing through the buckle, and a pair of spaced swingable link connections between the main frame and the frame extension on each side of the tool with the spaced links of each pair having spaced pivotal connections at one end with the main frame and at the other end with the frame extension to provide swinging movement of the frame extension with respect to the main frame in angular adjustment of the frame extension with respect to the main frame.
